FLOATING COMPASS DIAL

Charles L. Huber, Elba, N. Y., assignor to Taylor
Instrument Companies, Rochester, N. Y., a cor-
poration of New York

Application March 12, 1951, Serial No. 14,466

Term of patent 14 years

(Cl. D52—1)

To all whom it may concern:

Be it known that I, Charles L. Huber, a citizen
of the United States of America, residing at Elba,
county of Genesee, State of New York, have
invented a new, original, and ornamental De-
sign for a Floating Compass Dial, of which the
following is a specification, reference being had
to the accompanying drawing, forming a part
thereof, wherein:

Fig. 1 is a face view of a floating compass dial,
showing my new design.

Fig. 2 is an edge view thereof.

I claim:

The ornamental design for a floating compass
dial as shown.

CHARLES L. HUBER.
